MAGNETIC LOCKS

Ronald Felson, 228-40 Montone Ave., Laurelton,
Queens, New York, N.Y.
Filed June 29, 1962, Ser. No. 206,252
6 Claims. (Cl. 70—276)

The present invention relates to novel and improved magnetic lock constructions and the keys therefor.

Locks of this class, have heretofore relied on gravity action to return the tumblers to locking position, upon the withdrawal of the key. If a burglar could shift the lock a half turn, and such is known to have been done with cylinder locks, should the lock be of the magnetic type, it would automatically open. Further, magnetic locks of the past could not be used for cabinets, chests, trunks and other movable box structures, because all you need do to have the lock open by itself, is to invert the lock by setting the object it is mounted on, upside down.

It is therefore the principal object of this invention to provide a novel and improved spring-less magnetic lock which will avoid the aforementioned objectionable incidents, for my new lock operates properly without the aid of gravity and its operates properly regardless of its position. Further, gravity action will never open the lock regardless of how the lock's position is shifted. My new lock construction operates properly wholly by magnetic action and hence the line of tumbler movement may even be up to lock, or horizontal, because gravity action is never relied on.

A further object of this invention is to provide a novel and improved magnetic lock construction having the stated attributes, which is simple in construction, reasonable in cost and efficient in carrying out the functions for which it is designed.

Other objects and advantages will become apparent as this disclosure proceeds.

This invention is applicable in lock constructions of the type which operate on the principle that when a magnetic insert in the shank of a key is properly positioned, it will react with a magnetized tumbler so that the tumbler will move, whereupon that element of the lock which is adapted to shift a bolt or the like, is released for movement.

For the practice of this invention, each tumbler is permanently magnetized. The key has permanently magnetized inserts, one for each tumbler respectively, and so arranged that upon insertion of the key into the lock, the tumblers are repelled into unlocking position. Fixed on the lock casing, are auxiliary permanent magnets, one for each tumbler respectively, and so arranged that each constantly repels its related tumbler into locking position when the key is withdrawn. At all times, the tumbler is under the repelling action of its related auxiliary magnet. Of importance is that in each such set of three related magnets, the strength of the auxiliary magnet is sufficient to maintain the tumbler in locking position regardless of the line of movement of the tumbler, and the strength of the magnetic key insert is sufficient to shift the tumbler into unlocking position against the action of the auxiliary magnet regardless of the line of movement of the tumbler. These magnet strength relationships must also prevail regardless of the direction the tumbler need move at any time.

For a preferred embodiment of this invention, I show herein its adaptation in a cylinder lock construction. As a further feature, I provide that the key can be withdrawn, only that thereupon, the device is in locked condition.

In the accompanying drawing forming part of this

2

specification, similar characters of reference indicate corresponding parts in all the views.

FIG. 1 is an enlarged longitudinal view showing a cylinder lock embodying the teachings of this invention, and also its key. This view is shown in section taken at line 1—1 in FIG. 3. The key is shown entering the barrel. The tumblers are in locking position.

FIG. 2 is a fragmentary view of the device as shown in FIG. 1, but here in FIG. 2, the key is shown fully inserted and hence the tumblers are in their moved position and the barrel is free to turn in the casing.

FIG. 3 is a section taken at line 3—3 in FIG. 1.

FIG. 4 is like FIG. 3, except that the lock is shown inverted, yet the tumblers remain in their locking position.

FIG. 5 shows a front view of the lock, that is, looking onto the left end in FIG. 1. In this FIG. 5, the key is shown partly turned from its initial position at full insertion. Of course, the barrel has turned with the key.

FIG. 6 is a fragmentary perspective view which shows the front end portion of the barrel.

FIG. 7 is a fragmentary section only of the casing, taken at line 7—7 in FIG. 5.

In the drawing, the numeral 15 indicates generally a lock's cylinder or casing in which a barrel 16 is rotatably fitted, and as is well known, said barrel carries a suitable member 17 to shift the lock's bolt not shown, upon rotation of said barrel within the casing. Said barrel and casing are of non-magnetic material and so is the body of the key 18 which is slidable into and out of the barrel. There are a series of holes through the wall of the casing 15, one such hole being shown at 19, which series, at one position of the barrel 16, register respectively with radial sockets in said barrel 16, as for instance the socket 19' with the hole 19. Each hole and its related socket are of like diameter, adapted to house a slideably permanently magnetized tumbler which is of a length greater than the distance it can enter into the socket, so such tumbler can be part in the socket and part in the related hole of the cavity. Those holes having a tumbler, are closed by a permanent magnet as indicated at 20', so the tumbler is within a chamber. There is sufficient chamber space to allow the tumbler to reside wholly within the hole in the casing, as do the tumblers 20 and 21 in FIG. 2, in their respective holes 22 and 23. It is evident that when the tumblers extend in to the sockets, as in FIG. 1, they are in locking position, holding the barrel 16 fast in the casing 15, and that when the tumblers are out of the sockets in the barrel, they unlock the barrel and let it free for turning, as is the condition shown in FIG. 2. The key 18 has permanently magnetized inserts in the same spaced relation as the tumblers so that upon full insertion of the key into the barrel 16, one of such inserts is in axial alignment with one of the tumblers respectively.

The holes containing the tumblers 20, 21 and 24, are in one row along the casing 15, with the holes 19 and 25. If desired, tumblers may be provided in said holes 19 and 25, and such, together with the tumblers 20, 21 and 24, may constitute the entire locking means. Of course, wherever there is a tumbler, there is a companion auxiliary fixed magnet, as for instance the pair 20, 20'. However, in the illustrated embodiment, I have provided a second series of holes in another row along the casing 15, with companion sockets in the barrel 16, such sockets being indicated by the respective numerals 26—30, and have provided the tumblers 31 and 32 to be in staggered relation with the tumblers 20, 21 and 24, thereby leaving half the holes empty. It is evident that different choices of which holes in the casing are to contain tumblers, affords many combinations for the lock, each of which

needs its special key respectively. The spaced magnetic inserts positioned transversely through the body of the smooth key shank, are in such relative positions that when the key 18 is fully inserted into the barrel 16, one of said inserts is in alignment with one of the tumblers respectively.

An important teaching of this invention is that the magnetic components of this lock shall comprise sets of three magnet pieces each, namely a tumbler, an auxiliary fixed magnet on the casing and a magnetic insert in the key. In each set, the tumbler is under the repelling action of its related auxiliary magnet, and when the key is fully inserted in the barrel, the tumbler is under the repelling action of the related key insert; the strength of the auxiliary magnet being sufficient to maintain the tumbler in locking position regardless of the line and direction of movement of the tumbler, and the strength of the magnetic key insert, being sufficient to shift the tumbler into unlocking position against the action of the auxiliary magnet, regardless of the line and direction of movement of the tumbler. It is evident that the effects of gravity are counteracted in such a setup.

I will now identify such sets of three magnet components each. The tumbler 20 is related with the auxiliary magnet 20' and the magnetic key insert 20''. The tumbler 21 is related with the auxiliary magnet 21' and the magnetic key insert 21''. The tumbler 24 is related with the auxiliary magnet 24' and the magnetic key insert 24''. The tumbler 31 is related with the auxiliary magnet 31' and the magnetic key insert 31''. The tumbler 32 is related with an auxiliary magnet not shown, and with the magnetic key insert 32''.

At the finger-piece end, there is a pin 33 transversely through the shank of the key 18. This pin extends out of the shank, more at 33' than at 33'' to determine the position the key is to be in, so that when inserted into the barrel 16, the inserts 20'', 31'', 21'', 32'' and 24'' shall respectively be in alignment with the tumblers 20, 31, 21, 32 and 24. Upon such insertion of the key 18, all the tumblers will be shifted clear of the barrel 16 and into the holes in the body of the casing 15, that is, the tumblers will move from their normal locking position shown in FIG. 1 when the key 18 is out, to unlocking position shown in FIG. 2, effected by mere insertion of the key in proper position to register with the tumblers.

The casing 15 at front end, has the counterbore 38 into which the outward flange 39 at the front end of the barrel 16 rotatably fits, and a bit behind such counterbore, the casing is provided with an internal annular channel 35, along which the tip end portion of pin part 33' rides fitted therein, upon turning the key 18, after such key is fully inserted into the barrel. The radial distance from the floor of the channel 35 to the axis of the key, is a bit greater than the radius of the barrel's front flange 39. So there is a notch 36' to afford entrance of the distal end of the pin part 33' into said channel; such notch being in the face plate 34, and enterable at the front of such plate. The barrel 16 has a short keyway 37 enterable at the front end by the pin part 33'', and of a depth, just to admit it. For entrance of the pin part 33', the barrel has a notch 36 enterable at the front end. The length of said keyway 37 and the depth of said notch 36 are such that when the key is fully entered into the barrel, the distal end of the pin part 33' will enter the channel 35 when the key is then turned. Said notch 36 and keyway 37 are of course so positioned that they receive the pin 33 when the key is fully inserted in the barrel. The notch 36' in the casing is so positioned that it registers with the notch 36 when the pin tumblers are in locking position. In normal manufacture, the "keyhole" offered by the notches 36, 36' and the keyway 37, shall admit the pin 33 when the latter is vertical, in order to conform with ordinary lock practice to have the key in the vertical plane for insertion. It is evident that the key can be inserted only in one way, since the keyway 37 will not admit the pin part

33', but can only admit the pin part 33'' which is much shorter than 33'.

Upon full insertion of the key 18 into the barrel 16, meaning that the pin part 33'' is at the end of the keyway 37, the pin part 33' is at the closed end of the notch 36 and the distal end of said pin part 33' is in the annular channel entrance 36', the key's magnetic inserts are in their proper location to effect tumbler shift to unlocked position as in FIG. 2. So mere insertion of the key as mentioned, will release the barrel 16 for turning. Now upon turning the key, the barrel will turn and the incident movement of the member 17, will operate the bolt mechanism not shown. The distal end of the pin part 33' will be cached in the annular channel 35. It is evident that in this structure as illustrated, the key cannot be withdrawn except when the tumblers would be in locking position as in FIG. 1, upon the withdrawal of such key, and to withdraw the key, it must be in position to have the pin part 33' leave through the notch 36'.

It is to be noted that the action of gravity will never cause any tumbler to shift from locking position to unlocking position. So even if the device is inverted as in FIG. 4, the tumblers will remain in locking position, and it is also evident that the tumblers may be arranged for movement along the horizontal, since at no time is gravity action relied on to operate the device in any particular. Hence locks embodying this invention, may be used on cabinets, chests and the like, because turning the cabinet upside down, will not release the barrel 16. I have indicated the arrangement for the magnetic components, by marking polarities thereof "N" and "S." Of course, many other dispositions may be made to get different lock combinations, but always, the magnetic forces acting on a tumbler are repulsions from its associated auxiliary magnet and from its actuating magnet insert in the key. Of importance to note, is that regardless how the lock is installed, said auxiliary magnets maintain the tumblers in locking position when the key is out, whether tumbler movement is along the horizontal, or require to be acted on by an upward force to stay in locking position or require a force in any direction to stay in locking position, and said auxiliary magnets always do their job regardless of any shift in lock position. These incidents of structure and mode of operation, make this lock pick-proof.

This invention is capable of numerous forms and various applications without departing from the essential features herein disclosed. It is therefore intended and desired that the embodiment shown herein shall be deemed merely illustrative and not restrictive and that the patent shall cover all patentable novelty herein set forth; reference being had to the following claims rather than to the specific description herein to indicate the scope of this invention.

I claim:

1. In a magnetic lock device, a first member, a second member movably mounted on the first member; said members being of non-magnetic material; the first member having a hole therethrough and the second member having a socket therein in alignment with said hole, a permanently magnetized tumbler longitudinally slidable and fitted in said hole and socket, and positioned part in said hole and part in said socket, an auxiliary permanent magnet positioned fixed in said hole, away from said tumbler a sufficient distance to permit the tumbler to be entirely within said hole, in combination with a key of non-magnetic material having a permanently magnetized insert, means on said key and second member which come into alignment upon placing said key so that its magnetic insert is in alignment with said tumbler, and upon such positioning of the key and when said tumbler is entirely within said hole in the first member, the key can be manipulated to move the second member in relation to the first member; said tumbler and auxiliary magnet being so arranged that the tumbler is repelled by said auxiliary magnet; said magnetic key insert being so positioned when said means

come into alignment, that the tumbler is repelled by said magnetic insert; the strength of the auxiliary magnet being such that regardless of the line and direction of movement of the tumbler to leave the socket, said auxiliary magnet will act on the tumbler to maintain it entered into the socket when said socket and hole are in alignment and said means are out of alignment; the strength of said magnetic insert being such that regardless of the line and direction of movement of the tumbler to leave the socket, said insert will act on the tumbler to maintain it wholly in said hole when said means come into alignment, regardless of the action on the tumbler by said auxiliary magnet.

2. A magnetic lock device as defined in claim 1, wherein in the first member is a casing and the second member is a barrel rotatably fitted in said casing; the mentioned hole being through the wall of said casing; said barrel having a bore therein therealong and said bore being accessible for the admission of the key therein.

3. A magnetic lock device as defined in claim 2, wherein in the mentioned means is provided by having an internal annular channel in the casing near that end thereof into which the key is inserted in the bore of the barrel; there being a notch in the casing, providing an entrance for movement in a direction along the barrel, into said annular channel and by having a notch in that end of the barrel into which the key is inserted and also by having a pin extending laterally from the key; said notches being aligned when the tumbler is in locking position and the key is withdrawn; said pin being of a size to be entered and fitted in said notches when the key is fully inserted into the barrel; the direction of the magnetic insert in the key being such that upon full insertion of the key so that said pin shall be entered in both said notches, said magnetic insert shall be in alignment with the tumbler, whereupon inserting the key into the bore in the barrel, so that said pin is entered in both said notches, said tumbler will be shifted into unlocked position thus freeing the barrel for rotation in the casing and then upon turning the key, the distal end of said pin will enter said annular channel; said pin being of a size to ride fitted in said channel as it moves along such channel, whereby the key once fully inserted into the barrel, can be withdrawn therefrom only when said hole and socket are in alignment to allow the tumbler passage into said socket.

4. In a magnetic lock device, a first member, a second member movably mounted on the first member; said members being of non-magnetic material; the first member having a hole therethrough and the second member having a socket therein in alignment with said hole, a permanently magnetized tumbler longitudinally slidably and fitted in said hole and socket, and positioned part in said hole and part in said socket, an auxiliary permanent magnet positioned fixed in said hole, away from said tumbler

a sufficient distance to permit the tumbler to be entirely within said hole; said tumbler and auxiliary magnet being arranged that the tumbler is repelled by said auxiliary magnet, in combination with a key of non-magnetic material having a permanently magnetized insert; said key when placed in a position so that its magnetic insert is in alignment with said tumbler and acting to repel said tumbler so the tumbler is moved entirely within said hole in the first member, the second member will thereby be released for movement in relation to the first member; the strength of the auxiliary magnet being such that regardless of the line and direction of movement of the tumbler to leave the socket, said auxiliary magnet will act on the tumbler to maintain it entered into the socket when said socket and hole are in alignment and said key is away from said position; the strength of said magnetic insert being such that regardless of the line and direction of movement of the tumbler to leave the socket, said insert will act on the tumbler to maintain it wholly in said hole when said key is in said position, regardless of the action on the tumbler by said auxiliary magnet.

5. A magnetic lock device as defined in claim 4, wherein in the first member is a casing and the second member is a barrel rotatably fitted in said casing; the mentioned hole being through the wall of said casing; said barrel having a bore therein therealong and said bore being accessible for the admission of the key therein.

6. In combination with a magnetic lock device of the type whose tumblers are permanently magnetized and whose key has permanently magnetized inserts, one for each tumbler, adapted upon proper positioning of the key, to cause all the tumblers to move from locking to unlocking position, of auxiliary magnets, one for each tumbler, each auxiliary magnet acting to move and hold its related tumbler into locking position; the action of each auxiliary magnet on its related tumbler being in repulsion, the action of each key magnetic insert on its related tumbler being in repulsion and effective to shift such tumbler when the key is so properly positioned, to shift such tumbler from locking to unlocking position against the action of the related auxiliary magnet, such repulsion actions being effective to accomplish their stated functions respectively, regardless of the line and direction of movement of the tumblers to move from locking to unlocking position.
